UNITED STATES PATENT OFFICE.

JAMES F. McELROY, OF ALBANY, NEW YORK, ASSIGNOR TO CONSOLIDATED CAR-
HEATING COMPANY, A CORPORATION OF WEST VIRGINIA.

MAGNETIC SWITCH.

1,135,201.

Specification of Letters Patent.

Patented Apr. 13, 1915.

Application filed November 14, 1911. Serial No. 660,271.

To all whom it may concern:

Be it known that I, JAMES F. McELROY, a citizen of the United States, residing at Albany, county of Albany, State of New York, have invented certain new and useful Improvements in Magnetic Switches, the following being a full, clear, and exact disclosure of the one form of my invention which I at present deem preferable.

10 For a detailed description of the present form of my invention, reference may be had to the following specification and to the accompanying drawing, which illustrates my invention.

15 Figure 1 is a plan view of my device; Fig. 2 is a longitudinal section thereof showing the transfer switch in elevation; Figs. 3, 4 and 5 show enlarged details; Fig. 6 is a diagram of the switch and its circuits.

20 My invention relates to magnetically operated switches, such as may be used, for example, to open and close the circuit of an electric heater under the control of a thermostat.

25 Referring to the drawings A and B represent two solenoid magnets which may be of any well known construction but are shown herein as of the form shown in my application for patent Ser. No. 612,810, filed

30 March 7, 1911, and no claim thereto is made in the present application. These magnets have in common a reciprocating core C which is drawn in one direction or the other according as coil A or coil B is energized.

35 On core C is mounted a casting D which serves as a contact carrier for the movable contacts of the switch that the solenoids serve to operate. The carrier D is shown on an enlarged scale in Fig. 3. In its upper

40 part is clamped an insulated blade F under the plate d. The two ends of the blade F, when moved to the left by the energizing of solenoid A, will engage the fixed contact clips f and f¹ respectively (see Figs. 1 and

45 2). Each of these clips, as appears in Fig. 2, comprises two parallel springs, each having an inturned contact-plate g riveted to its extremity. These contact-plates g are inclined toward each other so that when the

50 blade enters between them they will be slightly forced apart and, by the yielding of the springs which carry them, will seat themselves firmly and flatly against the opposite sides of the blades. The circuit which

55 the switch is to control will be closed by this

engagement of blade F with contacts f, f¹ and opened when the blade is withdrawn.

In order to provide for the alternate operation of magnets A and B it is necessary that each one, after its action is completed, shall break its own circuit but close the circuit of the other magnet which is to act next to throw the core in the reverse direction. The contacts for effecting this transfer of the operating circuit from one magnet to the other compose what I designate herein as the transfer switch and I so construct such switch that there is no practical possibility of either magnet breaking its own circuit until it has completed its full stroke, nor of failing to do so when its stroke is completed. The closure of the circuit of the other magnet is equally insured. For this purpose the moving contacts are so managed as to follow different routes on their "in" and "out" strokes passing on one stroke beneath a spring trap which forces them on the return stroke to follow a different route along the back of the spring which forms one side of the trap.

Turning again to the drawings, particularly Fig. 3, there is shown on the under side of the aforesaid carrier D a block G of insulating material and underneath this block G is attached a plate J (see Figs. 4 and 5) to which are pivoted two spring contact-arms H and H¹. A second similar plate, with similar spring contact-arms h and h¹ thereon, is also attached to the block G on its underside beyond the aforesaid plate J, affording in all four spring contact-arms H, H¹, h, h¹ which coöperate with the stationary trap-contacts which I will now describe, one of them being shown in detail in Figs. 4 and 5, and the others being similar thereto. P is a base-plate set on a block of insulation M in the bottom of the switch-box beneath core C. Mounted edgewise and diagonally on this base-plate P is a trap-spring R, and also mounted edgewise and diagonally on the base-plate is a metal block K against which the spring R bears. The diagonal spring and the diagonal block form a V-shaped passage opening toward the contact-arm H whose depending end, when moved forward to the right will enter the said passage and being drawn over by its spring will come into contact with and bear against block K. A like V-shaped passage, formed by trap-spring R¹ and block K¹,

which are mounted on base-plate P, which will be presented to arm H¹, and the two arms being drawn together by their spring, the arm H¹ will come into contact with and bear on block K¹.

Since the arms H and H¹ are in electrical communication through plate J, the arms will establish connection between blocks K and K¹ whose respective base-plates P and P¹ are mounted separately on insulating block M and form terminals of the circuit to be closed, as I will explain hereinafter. This connection will continue as the arms H, H¹ move forward into the V-shaped passages and lift and pass under the spring plates R, R¹ and when those plates spring back behind the arms, the latter are caught or trapped and can not return by the same route. They will remain in the position thus reached, maintaining the closure of the circuit at that point, although the said circuit (which is the one that is to act subsequently to energize magnet coil A and so produce the reverse movement of the contacts H and H¹) is still open at the thermostat or controlling switch. The above described movement of arms H and H¹ toward the right into the trap-contacts has been produced by magnet-coil B, the circuit of which has been closed in like manner at the other set of trap-contacts and is closed also at the thermostat, or controlling switch. The other set of trap-contacts are, however, reversed in position so that the V-shaped passage opens away from the contact-arms h and h¹. Hence at the beginning of the aforesaid movement to the right the contact-arms h and h¹ are in the trapped position outside of the springs r and r¹, that being the position in which the above description left the contact-arms H and H¹. This is illustrated in Fig. 6 which shows the condition at the beginning of the movement to the right aforesaid before H and H¹ advanced into the V-shaped trap-passage. Consequently, while arms H and H¹ are moving into the said passage the corresponding arms h and h¹ are moving along the outside of their trap-springs r and r¹ respectively and maintaining closed the circuit of magnet-coil B which produces the said movement. At the end of said movement to the right the arms h and h¹ will snap off the rear ends of spring-plates r and r¹, as shown by dotted lines in Fig. 6. This will break the circuit of magnet B which has produced the said movement to the right, but manifestly such break will not occur until the said movement has been completed. In the meanwhile the break in the circuit of magnet A has been closed, as above described, by the engagement of contact-arms H and H¹ with their, trap-contacts. The parts will remain in the condition thus reached until the circuit of magnet A is finally closed at the thermostat

or controlling contacts. Thus the said movement to the right has, in the case herein illustrated, opened the main circuit of the electric heater at the main switch formed by blade F and contacts f and f¹ and the heaters thereby put out of action. When, however, the temperature of the car or apartment which the heaters serve has fallen low enough to cause the thermostat to close the circuit of magnet-coil A, then that magnet will act and the reverse stroke of the contact-arms H, H¹ will follow along the back of the trap-springs R, R¹ until they snap off the rear ends thereof. This will break the circuit of coil A but only after the coil has completed its work of moving the core C and contacts thereon to the extreme left position and thereby closing the circuit of the heater. The same movement will, in the way already described, close the break in the circuit of magnet coil B preparatory to the subsequent energizing of that coil when the thermostat moves in the opposite direction, in response to the heating action of the heaters, to finally close the circuit of said coil B.

In Fig. 6 Y represents the electric heater, the circuit thereof (controlled by a permanent switch a) being indicated by single-barbed arrows. X represents the thermostat, the tongue of which receives current from the main line via fuse a¹ and delivers that current either to magnet-coil A via the circuit identified by double-barbed arrows, or to magnet-coil B via the circuit identified by triple-barbed arrows.

What I claim as new and desire to secure by Letters Patent is:

1. An electrical switch comprising relatively reciprocable contact arms and contact blocks, means connected with said arms for holding them in engagement with said blocks during movement in one direction, and trap members connected with said blocks to automatically disengage said arms and blocks during the return movement, said trap members permitting reengagement of the arms and blocks at the end of the return movement.

2. An electrical switch comprising relatively reciprocable contact arms and contact blocks, means connected with said arms for holding them in engagement with said blocks during movement in one direction, and resilient trap members connected at one end to said blocks and having their other ends bearing against the blocks to automatically disengage said arms and blocks during the return movement, said trap members permitting reengagement of the arms and blocks at the end of the return movement.

3. An electrical switch comprising contact blocks, contact arms mounted on a reciprocable support and having traveling contact

with said blocks when moving in one direction, said contact arms being movable relative to each other, and contact means co-operating with said contact blocks for disengaging said contact arms from said blocks during the return movement of said arms, and permitting reengagement at the end of said return movement.

4. An electrical switch comprising contact blocks, a reciprocal support, contact arms pivotally connected at one end to said support, the other ends of said arms having traveling contact with said blocks when the support moves in one direction, said contact arms being movable relative to each other, and contact means co-operating with said contact blocks for disengaging said contact arms from said blocks during the return movement of said arms and permitting reengagement at the end of said return movement, and a spring connecting said contact arms.

5. An electrical switch comprising a base having spaced apart stationary contact blocks, a reciprocal support provided with contact arms having traveling contact with said blocks when moving in one direction, trap contacts secured to said base for disengaging the contact arms from said contact blocks, and permitting reengagement at the end of the return movement, and means for relatively positioning the contact arms to engage the contact blocks and the trap contacts respectively.

6. An electrical switch comprising elongated stationary contact blocks in spaced relation, traveling contact arms for engaging the contact blocks when moving in one directions, means connecting the traveling contact arms for positioning the latter to engage the contact blocks, and means for causing the contact arms to be disengaged from the contact blocks during the return movement and until the completion of said movement.

7. An electrical switch comprising a pair of diverging stationary contact blocks, movable contact arms arranged to engage said blocks during movement in one direction, trap contacts co-operating with the stationary contacts to disengage the contact arms from the contact blocks during the return movement thereof and permitting reengagement at the end of said return movement, and means connecting the contact arms to cause them to engage the trap contacts during the return movement.

8. An electrical switch comprising pairs of stationary contact blocks, the members of each pair diverging, pairs of movable contact arms corresponding to the contact blocks, and contacting therewith during movement in one direction, trap contacts for disengaging the movable contact members from the contact blocks during the return movement and permitting reengagement at the end of said movement, and means for causing the movable contact arms to normally engage the contact blocks, one pair of contact arms being in engagement with its contact blocks when the other pair of contact arms is in engagement with its trap contacts.

9. An electrical switch comprising contact blocks, contact arms mounted on a reciprocal support and having traveling contact with said blocks when moving in one direction, said contact arms being movable relative to each other, and trap contacts, each trap contact being secured at one end to the contact block, the free end resting yielding against its relative contact block.

In witness whereof I have hereunto set my hand, before two subscribing witnesses, this 10th day of November, 1911.

JAMES F. McELROY.
